UNITED STATES PATENT OFFICE

JOHN STRINDLUND, OF TOFTE I HURUM, NORWAY

BARKING DRUM

Application filed July 21, 1931, Serial No. 552,092, and in Sweden July 23, 1930.

The present invention relates to an improvement in barking drums of the type which consist of several substantially horizontal rotary drum sections arranged end to end.

It is well known that in barking drums the barking action is principally produced by friction between the logs, and since the strength of the bark is reduced when soaked with water, it is customary to carry out the barking operation in the presence of water. The barking operation takes place the easier, the wetter the bark is, and it will of course also be effected the speedier and better the greater the pressure between the logs is.

The present invention has for its purpose to render it possible to fill the barking drums to a higher level than hitherto possible, whereby several advantages are attained amongst which are that the wood is given more time in the barking drum and thus becomes better soaked with water, and that owing to the increased pressure the bark is more easily ground to pieces and thus more easily removed, which two advantages render it possible to drive the barking drum at a lower speed whereby the consumption of power is reduced.

The invention consists principally in that the drum sections, taken in the direction from the inlet end of the drum, lie with their axes higher than the axes of the following drum sections, or with their axes displaced to that side of the vertical plane through the axes of the following drum sections on which side the circumferences of the drum sections move downwards, or with their axes both displaced to said side and lying higher than the axes of the following sections.

In the accompanying drawings two embodiments of barking drums according to the invention are illustrated diagrammatically. Fig. 1 shows a longitudinal section of a barking drum the sections of which have equal diameters, and Fig. 2 is a diagrammatical end view of the drum. Fig. 3 shows a longitudinal section of a barking drum the sections of which have unequal diameters, and Fig. 4 is a diagrammatical end view of said drum.

The barking drum illustrated in Figs. 1 and 2 is shown as consisting of five drum sections 1, 2, 3, 4, and 5, numbered in the direction from the inlet end of the drum. As shown in Fig. 2, the section 1 lies with its axis A1 higher than the axis A2 of the section 2, and also has its axis A1 displaced to the left of the vertical plane through the axis A2 of the section 2, that is to say on that side of the vertical plane through said axis A2 on which side the circumferences of the sections move downwards, as indicated by the arrow 10. In similar manner the section 2 lies with its axis A2 higher than and to the left of the axis A3 of the section 3. The various sections are supported by chains 8 running over chain wheels 6 on shafts 7 and are also supported at their ascending sides by supporting rollers 9.

As is well known, a horizontal rotary barking drum can be filled with logs up to a certain level or surface which is inclined during the rotation. Said level or slanting surface up to which the section 1 may be filled, is referenced 11 in Fig. 2, and the corresponding levels or surfaces in sections 2 and 3 are referenced 12 and 13, respectively. According to the present invention the barking drum may thus be operated with the sections filled up to these highest levels or slanting surfaces 11, 12, and 13, whereby the advantages above stated are attained, and simultaneously such slope is obtained in the longitudinal direction of the barking drum of the inclined upper surface of the wood, which surface is denoted by said lines 11, 12, and 13, that the logs are given a high speed of motion in the axial direction through the barking drum, which is necessary in drums of great lengths, and which has also proved to produce a considerably increased efficiency of the barking operation which result appears to be due to the fact that the logs will then place themselves more parallel to each other and to the drum.

As shown in the drawings, each drum section has entirely open and unconstricted ends, so that there may be a free and unrestricted flow of the mass

of logs from one section to another. The drum sections are provided at their adjacent ends with exterior flanges which are arranged in such manner, as shown in Fig. 5 1, that the flange on one section covers that portion of the end opening of the adjacent section which is not covered by the first section. By this arrangement the logs are prevented from getting jammed between the various sections.

The same result, though in a somewhat less degree, can obviously be obtained by locating the axis of each section to the left, as viewed in Fig. 2, of the axis of the following section, as shown in respect of sections 3 and 4 where the axis A3 of section 3 is located to the left of the axis A4 of section 4, since also with this arrangement the filling line or surface 13 of the preceding section 3 will come higher than the filling line or surface 14 of the following section 4.

In order to obtain a sufficient outlet opening over the wall 16 it is suitable to place one or more of the last section of the series, section 5 in Figs. 1 and 2, higher than the preceding section 4, and preferably also somewhat to the left of the same, as shown in Fig. 2 where A5 is the axis of section 5.

The barking drum illustrated in Figs. 3 and 4 differs from the one above described and illustrated in Figs. 1 and 2 only in so far that the sections 21 and 22 at the inlet end and the section 25 at the outlet end have larger diameters than the middle sections 23 and 24. Lines 31, 32, 33, and 34 in Fig. 4 denote the filling surfaces in sections 21, 22, 23, and 24, respectively. This construction operates in the same manner as that above described.

40 I claim:

1. In a barking drum having an inlet end and an outlet end, the combination of several substantially horizontal rotary drum sections arranged end to end, each drum section having entirely open and unconstricted ends, the section nearest the inlet end of a pair of adjacent drum sections having its axis located higher than the axis of the other of said drum sections in the direction perpendicular to the slanting level formed by the rolling wood in the drum when rotated.

55 2. In a barking drum having an inlet end and an outlet end, the combination of several substantially horizontal rotary drum sections arranged end to end, each drum section having entirely open and unconstricted ends, the section nearest the inlet end of a pair of adjacent drum sections having its axis located higher in the vertical direction than the axis of the other of said drum sections.

60 3. In a barking drum having an inlet end and an outlet end, the combination of several substantially horizontal rotary drum sec-

tions arranged end to end, the section nearest the inlet end of a pair of adjacent drum sections having its axis located higher in the vertical direction than the axis of the other of said drum sections and also displaced to that side of the vertical plane through the axis of said other drum section on which side the circumferences of the drum sections move downwards.

75 4. In a barking drum having an inlet end and an outlet end, the combination of several substantially horizontal rotary drum sections arranged end to end, the section nearest the inlet end of a pair of adjacent drum sections having its axis located higher than the axis of the other of said drum sections in the direction perpendicular to the slanting level formed by the rolling wood in the drum when rotated, and a drum section at the discharge end of the drum having its axis located higher than the axis of the preceding drum section.

80 5. In a barking drum having an inlet end and an outlet end, the combination of several substantially horizontal rotary drum sections arranged end to end, the section nearest the inlet end of a pair of adjacent drum sections having its axis located higher than the axis of the other of said drum sections in the direction perpendicular to the slanting level formed by the rolling wood in the drum when rotated, said drum sections being provided at their adjacent ends with exterior flanges adapted to cover such portion of the end opening of one section as is not covered by the adjacent section.

85 6. In a barking drum having an inlet end and an outlet end, the combination of several substantially horizontal rotary drum sections arranged end to end, the section nearest the inlet end of a pair of adjacent drum sections having its axis located higher in the vertical direction than the axis of the other of said drum sections, said drum sections being provided at their adjacent ends with exterior flanges adapted to cover such portion of the end opening of one section as is not covered by the adjacent section.
